Primary Examiner—Janice E. Seeger
Attorney, Agent, or Firm—Trapani & Molldrem[57] **CLAIM**

The ornamental design for a square cocktail table with inlaid stone top, as shown and described.

DESCRIPTION

FIG. 1 is a perspective view of a square cocktail table with inlaid stone top, showing my new design;

FIG. 2 is a top plan view thereof; and,

FIG. 3 is a front elevational view thereof, the rear elevational view and side elevational views being identical.

The bottom of the table is plain and unadorned.
